UNITED STATES PATENT OFFICE.

LARS W. BODINSON, OF AURORA, ILLINOIS, ASSIGNOR TO THE AMERICAN WELL WORKS,
OF AURORA, ILLINOIS, A CORPORATION OF ILLINOIS.

CENTRIFUGAL PUMP.

1,221,822.

Specification of Letters Patent. Patented Apr. 10, 1917.

Application filed June 22, 1911. Serial No. 634,734.

To all whom it may concern:

Be it known that I, LARS W. BODINSON, a citizen of the United States, residing at Aurora, in the county of Kane and State 5 of Illinois, have invented certain new and useful Improvements in Centrifugal Pumps, of which the following is a specification, reference being had to the accompanying drawings.

10 My invention relates to centrifugal pumps designed more especially for pumping water at high pressure. It has for its object to provide an improved construction of pump in which the end thrust upon the pump- 15 shaft and runner or runners due to suction is automatically counteracted so that the runners are balanced and undue lateral friction is avoided. My invention also provides means for adjusting the counteracting 20 mechanism so that the balance of the pump may be maintained notwithstanding variations in the end thrust due to unequal pressure or suction on the runners or impellers. I accomplish this object as illus- 25 trated in the drawings and as hereinafter described. That which I believe to be new is set forth in the claims.

In the accompanying drawings,—

Figure 1 is a side elevation of my im- 30 proved pump, the discharge pipe being in section;

Fig. 2 is a longitudinal vertical section thereof; and

Fig. 3 is a partial vertical section show- 35 ing the pump provided with means for adjusting the counteracting mechanism or bal- ancing means.

40 My improved pump comprises a pump- shaft mounted in suitable bearings and pro- vided with one or more runners or impellers which are fixedly mounted on the shaft and by their rotation operate to lift the water from the well by suction. The runners are arranged in several chambers which com- 45 municate with one another successively, the last chamber discharging into an outlet pipe. In the construction shown the shaft is mounted in a horizontal position and is connected with a suitable source of power, such 50 as a motor, by a flexible coupling. Ob- viously, when the pump is in operation the suction due to the rotation of the runners

creates a tendency in the shaft to move end- wise toward the inlet and this, if not com- pensated for, will cause the runners to bear 55 against one side of the casing and cause friction. To counteract this effect I provide means acted upon by the water passing through the pump to move the shaft in the opposite direction,—such counteracting 60 means being properly proportioned so as to offset or neutralize the effect of unequal pressure or suction. Such counteracting mechanism comprises, in the construction shown, a disk or piston arranged in a bal- 65 ancing chamber separate from but com- municating with one of the runner chambers through a suitable passage, and connected with the pump-shaft, so that when the shaft is moved slightly toward the inlet end of the 70 pump by suction said piston acts to restrict the area of the outlet from said passage and consequently the pressure of the water tends to move the piston and shaft in the oppo- 75 site direction. A device is also provided 80 opposite the inlet to said passage, which acts to enlarge said inlet when the outlet is restricted and to restrict the area of the inlet when the outlet is enlarged. This operation continues throughout the operation 85 of the pump so that the practical effect is to maintain the shaft at all times in proper operative position.

Referring to the drawings,—

5 indicates a bed-plate or foundation on 85 which the pump is mounted. 6—7 indicate, respectively, the lower and upper members of the casing, which, in the construction shown, is made in two semi-cylindrical parts forming a longitudinally split housing. 90 The lower member 6 of the casing is pro- vided with an inlet 8 at one end, which com- municates with a suction pipe 9 and with an outlet 10 which communicates with a dis- 95 charge pipe 11, as shown in Fig. 1. 12 in- dicates a pump-shaft, which, as best shown in Fig. 2, is mounted in suitable bearings 13—14 of any suitable description. 15 indi- cates a flexible coupling provided at one 100 end of the shaft 12, by which it may be con- nected to a motor, or any other suitable source of power. This coupling forms no part of my present invention and any other suitable means may be employed for con-

necting the pump-shaft with the source of power. 16-17 indicate stuffing-boxes for preventing leakage around the shaft 12. 18-19-20 indicate runners or impellers, 5 which are mounted upon and keyed to the shaft 12, being placed thereon at suitable intervals and arranged to rotate, respectively, in runner or pressure chambers 21-22-23. 24-25 and 26-27 indicate 10 partitions or diaphragms which separate the interior of the casing into the several runner or pressure chambers, and 28-29 indicate passages through which water flows from the runner chamber 21 to the runner 15 chamber 22 and from the chamber 22 to the chamber 23, respectively, so that water entering the pump through the inlet 8 flows through runner chamber 21 to runner chamber 22 and thence to runner chamber 23 and 20 is then discharged through the outlet 10. The partitions 26-27 form one-piece circular division walls which possess important advantages over prior constructions in which such division walls are made in 25 halves in that they are cheaper to manufacture and make packing joints between the runner chambers unnecessary. The partitions 26-27 are held in place by machined shoulders 24^a-25^a-26^a-27^a on the inside 30 of the pump housing, and are held against rotation by dowel pins 28^a, as shown in Fig. 2. 30 indicates a sleeve screwed upon the pump-shaft 12, adjacent to the runner 35 18 for holding said runner in position on the shaft, and 31-32 indicate spacing sleeves mounted on the shaft 12 between runners 18-19 and 19-20, respectively. 33-34 indicate pipes leading from the stuffing-boxes 16-17 to and communicating 40 with the interior of the pump for forming water seals for said stuffing boxes.

35 indicates a balancing chamber at the outlet end of the pumping mechanism and partly separated therefrom by a diaphragm 45 or partition 36. 37 indicates a disk or balancing piston, which is mounted on the pump-shaft 12 in the chamber 35 and rotates with said shaft. The shaft 12, with the impellers and other parts carried by it, may be 50 termed the "rotor." 38 indicates a collar or hub also mounted on the shaft 12 and rotating therewith, said collar being placed in the runner chamber 23, as shown in Fig. 2. The collar 38 is of somewhat less diameter 55 than the piston 37, as shown in Fig. 2, and forms an annual shoulder which cooperates with a shoulder on the partition 36, as hereinafter described. 39 indicates a sleeve, which is fitted in the opening or passage in 60 the partition 36 around the shaft 12, its internal diameter being somewhat greater than that of the shaft 12 forming practically an extension thereof and of a sleeve 40 which, in the construction shown in Fig. 2, forms a

part of the piston 37, so that a communicating passage 41 is provided between the chambers 23 and 35, as shown in Fig. 2. The sleeve 39 is provided with two faces, its inner or left-hand face being arranged to cooperate with the opposing face of the collar or 70 hub 38 to form an inlet to the passage 41, while its outer or right-hand face cooperates with the opposing face of the piston 37 to form a pressure chamber leading to the waste chamber 35. It will be apparent that 75 the area of the inlet to the passage 41 is variable by longitudinal movement of the pump-shaft 12, as when said shaft moves to the right the collar 38 is moved toward the opposing face or shoulder of the sleeve 39, 80 reducing the area of the inlet to the passage 41 and closing such inlet completely if and when said parts are brought into close contact with each other. Movement of the pump-shaft in the opposite direction increases the area of the inlet. The outlet from the pressure chamber, formed by the piston 37 and the opposing face of the sleeve 39, which, as shown in Fig. 2, are preferably recessed, also varies with the longitudinal movement of the pump-shaft, but its variation is opposite to that of the inlet to the passage 41, since movement of the pump-shaft to the right carries the piston 37 away from the opposing face of the sleeve 95 39, while movement of the sleeve in the opposite direction moves the piston 37 toward the partition and consequently reduces the area of the outlet from said pressure chamber simultaneously with the enlargement of 100 the area of the inlet to the passage 41. The outlet from the pressure chamber will be entirely closed if the inner face or shoulder of the piston 37 is brought into close contact with the outer face or shoulder of the sleeve 105 39. By employing cooperating members having flat faces, a more effective operation is secured, since the opposing flat surfaces when in contact make a tight closure, and there is practically no wear such as occurs 110 where a piston sliding in a cylinder is used. The piston 37 and the collar 38 are set far enough apart so that when one of said parts is in contact with the adjacent face of the sleeve 39 the other member is separated 115 therefrom. When the parts are in a neutral position, as shown in Fig. 2, neither of said members is in contact with the sleeve 39. 42 indicates a pipe leading from the chamber 35 to the inlet passage 8, said pipe providing 120 means for discharging water admitted to the chamber 35.

The operation of the apparatus as thus far described is as follows: When the pump is in operation it acts to suck water up through 125 the inlet 8 and to discharge it through outlet 10. The effect of the suction is to give the shaft 12 a tendency to move to the left, as

shown in Fig. 2, thus enlarging the inlet to the passage 41 and reducing the area of the outlet from the pressure chamber with which the passage 41 communicates, thereby permitting water from the runner chamber 23 to flow freely through the passage 41 and act against the inner face of the piston 37 in opposition to the force tending to move the pump-shaft to the left. So long as the latter force predominates, the pump-shaft will move to the left, further closing the outlet from the pressure chamber and simultaneously enlarging the inlet to the passage 41 until the force causing the movement of the shaft to the left is neutralized and a state of balance is attained. If afterward the pump suction is reduced, the effect of the water pressure upon the piston 37 will tend to move the pump-shaft to the right, which, however, will at once enlarge the outlet from the pressure chamber and reduce the inlet to the passage 41 by moving the piston 37 and collar 38 to the right, thereby reducing the pressure upon the piston 37 until a state of equilibrium is again attained. These operations are repeated from time to time as during its operation the balance of the pump is disturbed. Of course the extent of movement of the shaft involved in this operation is very slight and is unobjectionable, but the practical effect of the operation is to maintain the runners in a balanced condition so that lateral friction is avoided.

In Fig. 3 I have illustrated the application to the balancing mechanism of means by which said mechanism may be adjusted when necessary. This construction differs from that first described only in that I employ a piston 43 which is practically the same as the piston 37 except that it is provided with a sleeve 44 mounted on screw-threads on a pump-shaft 45 which is similar in other respects to the shaft 12. Thus the space between the piston 43 and collar 38 may be varied and regulated to suit operating conditions. For holding the piston 43 in position, in addition to the screw-threads I provide a lock-nut 45^a and a set-screw 46, as shown in Fig. 3.

My invention is not to be restricted to the specific construction shown and described, except in so far as it is particularly claimed, but includes generically the subject-matter of the broader claims.

It will be understood that my improved balancing means may be applied to vertical as well as to horizontal pumps.

That which I claim as my invention, and desire to secure by Letters Patent, is,—

1. A centrifugal pump, comprising a pump-shaft, an impeller mounted thereon, a chamber in which said impeller rotates, a passage leading from the impeller chamber to a pressure chamber, and means operated

by movement of the pump-shaft toward the 65 pump inlet to enlarge the area of the inlet to said passage and reduce the area of the outlet from said pressure chamber, and vice versa.

2. A centrifugal pump, comprising a 70 pump-shaft, an impeller mounted thereon, a chamber in which said impeller rotates, a passage leading from the impeller chamber to a pressure chamber, means operated by movement of the pump-shaft toward the 75 pump inlet to enlarge the area of the inlet to said passage and reduce the area of the outlet from said pressure chamber, and vice versa, and a pipe for conducting the fluid discharged from said pressure chamber to 80 the pump inlet.

3. A centrifugal pump, comprising a pump-shaft, an impeller mounted thereon, a chamber in which said impeller rotates, a 85 partition at one side of said chamber having a passage therethrough, and means at opposite sides of said partition forming a variable inlet to said passage and a pressure chamber into which said passage discharges, said means being movable with the pump-shaft to inversely vary the area of the inlet 90 to said passage and the outlet from said pressure chamber.

4. A centrifugal pump, comprising a 95 pump-shaft, an impeller mounted thereon, a chamber in which said impeller rotates, a partition at one side of said chamber having a passage therethrough, means at opposite 100 sides of said partition forming a variable inlet to said passage and a pressure chamber into which said passage discharges, said means being movable with the pump-shaft to inversely vary the area of the inlet to said 105 passage and the outlet from said pressure chamber, and a pipe for conducting fluid discharged from said pressure chamber to the pump inlet.

5. A centrifugal pump, comprising a pump-shaft, an impeller mounted thereon, a chamber in which said impeller rotates, a 110 passage leading from the impeller chamber to a pressure chamber, and means mounted on the pump-shaft and operated by movement thereof toward the pump inlet to enlarge the area of the inlet to said passage 115 and reduce the area of the outlet from said pressure chamber, and vice versa.

6. A centrifugal pump, comprising a pump-shaft, a runner mounted thereon, a runner chamber having inlet and outlet 120 openings, a piston chamber, a partition between said runner and piston chambers, said partition having an opening around the pump-shaft, a sleeve fitted in said opening, the internal diameter of said sleeve being 125 greater than the diameter of the pump-shaft, a piston mounted on said pump-shaft in the piston chamber and movable longitudinally

with the pump-shaft toward and from one end of said sleeve, and a collar mounted on the pump-shaft adjacent to the opposite end of said sleeve and movable with the pump-shaft toward and from said sleeve.

7. A centrifugal pump, comprising a pump-shaft, a runner mounted thereon, a runner chamber having inlet and outlet openings, a piston chamber communicating with said runner chamber through a passage, a piston mounted on said pump-shaft in said piston chamber and movable longitudinally with the pump-shaft toward and from one end of said passage, means mounted on the pump-shaft opposite the other end of said passage and movable longitudinally with the pump-shaft to open or close said passage, and means for adjusting said piston longitudinally of the shaft.

8. A centrifugal pump, comprising a pump-shaft, a runner mounted thereon, a chamber in which said runner operates, said chamber having inlet and outlet openings, a piston mounted on said shaft, a chamber in which said piston operates, means coöperating with said piston for causing the same to be automatically moved away from the inlet opening by the pressure of the water pumped when the runner is moved by suction toward the inlet opening, and means for adjusting the position of the piston upon the shaft.

9. A centrifugal pump, comprising an endwise-movable shaft, a runner mounted thereon and rotating therewith, a chamber in which said runner operates, said chamber having inlet and outlet openings, a piston chamber surrounding said shaft and adapted to communicate with said runner chamber, a piston in said chamber and mounted on said shaft, means operated by the movement of the runner toward the inlet opening for subjecting said piston to the pressure of the water pumped, and means for adjusting the position of the piston upon the shaft.

10. A centrifugal pump, comprising an endwise-movable shaft, a runner mounted thereon, a runner-chamber having inlet and outlet openings, and manually adjustable means actuated by the pressure of the water pumped to move the runner away from the inlet openings.

11. A centrifugal pump, comprising a pump-shaft, a runner mounted thereon, a chamber in which said runner operates, said chamber having inlet and outlet openings, and a manually adjustable piston actuated by the pressure of the water pumped to counteract the effect of suction upon the runner.

12. A centrifugal pump, comprising a pump-shaft, a runner mounted thereon, a chamber in which said runner operates, said chamber having inlet and outlet openings, a

piston mounted on said shaft and manually adjustable thereon, a chamber in which said piston operates, and means coöperating with said piston for causing the same to be automatically moved away from the inlet opening by the pressure of the water pumped when the runner is moved by suction toward the inlet opening.

13. A centrifugal pump, comprising a runner chamber having inlet and outlet openings, a runner mounted in said chamber and movable toward and from the inlet opening, and manually adjustable means operated by the pressure of the water pumped to move the runner away from the inlet opening.

14. In a centrifugal pump, a rotor comprising an impeller and a balancing piston behind said impeller, a casing inclosing said rotor and having an inlet and a discharge, said casing having a partition projecting inward toward the machine axis and located between the balancing piston and the impeller to thereby form a balancing chamber between the partition and the piston, there being pressure chambers at the front and rear of the impeller in communication with the pump discharge, also a waste duct part of which is behind the piston, said waste duct leading from the rim of the piston to the pump inlet, a pair of coöperating annular shoulders one on said partition and the other on the rotor hub adapted to permit an increased flow from the rear pressure chamber into the balancing chamber when the rotor moves laterally forward toward the pump inlet and throttles the flow when the rotor moves rearward, and a second pair of coöperating annular shoulders one on said piston and the other on said casing adapted to permit an increased flow from said balancing chamber to said waste duct when said rotor moves rearward and throttle the flow when said rotor moves forward.

15. In a centrifugal pump, turbine, or similar machine, the combination of a casing having an inlet and a discharge, a rotary impeller coöperating with the casing to form a pressure chamber between the casing and the rear of the impeller, a balancing piston at the rear of the impeller moving in unison therewith, a centrally apertured removable partition plate in said casing forming the rear of said pressure chamber and the front of a balancing chamber, the rear of the balancing chamber being formed by said piston, a pair of interfitting shoulders, one formed on the impeller hub and the other at the central aperture of said plate, said shoulders being so formed as to increase the flow from the pressure chamber into the central aperture of the plate when the impeller moves laterally forward toward the inlet of the machine, a second pair of inter-

fitting annular shoulders one of which forms the rim of the piston and the other of which is formed on the said plate, said second pair of shoulders being so formed and located as to permit an increased flow from the balancing chamber when the piston moves rearward and a duct leading from the rim of the piston to the inlet of the machine.

16. A centrifugal pump, comprising a casing split longitudinally, a pump-shaft, an impeller mounted thereon, a chamber in which said impeller rotates, a partition at one side of said chamber composed of members integral with the members of the casing, a passage in the members of said partition through which the pump-shaft extends, a sleeve mounted on the pump-shaft and extending through said passage, said sleeve having members coöperating with the partition to form a variable inlet at one end of said passage, and a pressure chamber into which said passage discharges, said sleeve being movable with the pump-shaft to vary the area of the inlet to said passage and to inversely vary the outlet from said pressure chamber.

17. A centrifugal pump, comprising a shaft, an impeller mounted thereon, a casing forming a runner chamber and having an inlet and a discharge, a partition adjacent to said impeller chamber, a passage through said partition, a piston mounted opposite the discharge end of said passage and coöperating with said partition to form a pressure chamber, said piston being movable with said shaft toward and from said passage to vary the area of the outlet from said pressure chamber when said shaft moves longitudinally, and means carried by said shaft at the opposite end of said passage and movable toward and away therefrom to vary the area of the inlet to said passage when said shaft moves longitudinally, the arrangement being such that the inlet to said passage is restricted simultaneously with the enlargement of the outlet from said pressure chamber, and vice versa.

18. A centrifugal pump, comprising a shaft, an impeller mounted thereon, a casing forming a runner chamber and having an inlet and a discharge, a partition adjacent to said impeller chamber, a passage through said partition, a piston mounted opposite the discharge end of said passage and coöperating with said partition to form a pressure chamber, said piston being movable with said shaft toward and from said passage to vary the area of the outlet from said pressure chamber when said shaft moves longitudinally, means carried by said shaft at the opposite end of said passage and movable toward and away therefrom to vary the area of the inlet to said passage when said shaft moves longitudinally, the arrangement being

such that the inlet to said passage is restricted simultaneously with the enlargement of the outlet from said pressure chamber, and vice versa, and means for conducting the effluent from said pressure chamber to the pump inlet.

19. A centrifugal pump, comprising a shaft, an impeller mounted thereon, a casing forming a runner chamber and having an inlet and a discharge, a partition adjacent to said impeller chamber, a passage through said partition, a stationary member fitted in said passage and having inner and outer faces, a piston mounted opposite the discharge end of said passage and coöperating with the outer face of said stationary member to form a pressure chamber, said piston being movable with said shaft toward and from said stationary member to vary the area of the outlet from said pressure chamber when said shaft moves longitudinally, and means carried by said shaft at the opposite end of said passage and movable toward and from the inner face of said stationary member to vary the inlet to said passage when said shaft moves longitudinally, the arrangement being such that the inlet to said passage is restricted simultaneously with the enlargement of the outlet from the pressure chamber, and vice versa.

20. A centrifugal pump, comprising a shaft, an impeller mounted thereon, a casing forming a runner chamber and having an inlet and a discharge, a partition adjacent to said impeller chamber, a passage through said partition, a stationary member fitted in said passage and having inner and outer faces, a piston mounted opposite the discharge end of said passage and coöperating with the outer face of said stationary member to form a pressure chamber, said piston being movable with said shaft toward and from said stationary member to vary the area of the outlet from said pressure chamber when said shaft moves longitudinally, means carried by said shaft at the opposite end of said passage and movable toward and from the inner face of said stationary member to vary the inlet to said passage when said shaft moves longitudinally, the arrangement being such that the inlet to said passage is restricted simultaneously with the enlargement of the outlet from the pressure chamber, and vice versa, and a conduit for conducting the effluent from said pressure chamber to the inlet of the pump.

21. A centrifugal pump, comprising a shaft, an impeller mounted thereon, a longitudinally split casing forming a runner chamber and having an inlet and a discharge, a partition adjacent to said impeller chamber, a passage through said partition, a stationary member fitted in said passage and held in position by the members of the casing

and having inner and outer faces, a piston mounted opposite the discharge end of said passage and coöperating with the outer face of said stationary member to form a pressure chamber, said piston being movable with said shaft toward and from said stationary member to vary the area of the outlet from said pressure chamber when said shaft moves longitudinally, and means carried by said shaft at the opposite end of said passage and movable toward and from the inner face of said stationary member to vary

the inlet to said passage when said shaft moves longitudinally, the arrangement being such that the inlet to said passage is restricted simultaneously with the enlargement of the outlet from the pressure chamber, and vice versa. 15
